UNITED STATES PATENT OFFICE.

JOSEPH P. GLASER, OF DETROIT, MICHIGAN, ASSIGNOR TO CHAMBERLIN METAL WEATHER STRIP COMPANY, OF DETROIT, MICHIGAN.

WEATHER-STRIP.

1,379,911.

Specification of Letters Patent. Patented May 31, 1921.

Application filed September 27, 1917. Serial No. 193,522.

To all whom it may concern:

Be it known that I, JOSEPH P. GLASER, citizen of the United States, residing at 109 Third Ave., Detroit, in the county of Wayne and State of Michigan, have invented certain new and useful Improvements in Weather-Strips, of which the following is a specification, reference being had therein to the accompanying drawing.

10 This invention relates to improvements in weather strips and more particularly to the class of weather strips especially designed for casement windows and similar structures, in which coöperating metal strip elements are provided respectively upon the lower rail of the sash and the sill of the window frame.

15 The object of the invention is to provide a light cheap construction of the character referred to that will be strong and durable in use and will afford a very efficient seal and weather proof joint.

The invention will be understood from the following detail description when considered in connection with the accompanying drawings forming part hereof and wherein is illustrated a preferred embodiment of the invention and one modification thereof.

In the drawings:

30 Figure 1 is a vertical section of a casement window having applied thereto a weather strip constructed in accordance with the present invention, the window sash being shown in closed position.

35 Fig. 2 is a detailed perspective view of the sill strip, and

Fig. 3 is a similar detail view illustrating a modified form of sill strip.

Referring to a detail description of the drawings, wherein like reference characters designate corresponding parts throughout the several views, the special embodiment of the invention illustrated in Figs. 1 and 2 of the drawings, comprises a metal strip element A constructed of flexible sheet metal, such as sheet zinc, copper or the like, and having spaced upstanding double wall flanges a—b, an intermediate connecting portion a' and outstanding flanges a²—a³ at opposite sides, the upstanding flange a having its upper portion bent outwardly at substantially right angles, and the upstanding

flange b having its upper portion b' bent to extend at an upward inclination. The metal strip A is secured upon the upper face 55 of the sill of the window frame by any suitable means, shown in the present instance as rows of tacks passing through the intermediate connecting portion such as a', and the outstanding flange a³. 60

Secured upon the lower face of the sash rail C within the rabbet c for coöperation with the sill strip is a strip element D constructed of flexible sheet metal. This strip element has a rebent curved portion at one 65 side providing a substantially hook shaped part d forming a pocket at one side of the strip, and the strip at its other side has a downwardly inclined sealing portion d', the inclination of said sealing portion d' corre- 70 sponding to the angle of inclination of the upwardly inclined portion b' of the flange b of the sill strip. The sash rail E is provided with a second relatively small rabbet e at its lower outer marginal portion, and 75 the strip D is positioned so that the downwardly inclined sealing portion d' thereof extends from the inner wall of said rabbet e.

When the window sash is in its closed position, as shown in Fig. 1 of the drawings, 80 the upper outwardly bent portion a⁴ of the flange a extends within the hook part d of the sash strip D, the lower face of the forward part of said portion a⁴ fitting tightly against the one face of the outer portion of 85 the hook shaped part d, and the upper inclined portion b' of the flange b fitting tightly against the outer face of the downwardly inclined sealing portion d' of the sash strip D, said upper inclined portion b' 90 being disposed beneath the upper wall of the rabbet e and at its outer marginal edge making a tight fit with the upper and inner side walls of the rabbet.

The upstanding flange a is shown provided in the lower portion thereof with small openings a⁵, the purpose of said openings being to permit any moisture that may enter the channel between the upstanding flange to drain off to the other side of the 100 flange a.

In the modified construction illustrated in Fig. 3 of the drawings, the sill strip is made up of two separate strips or members

K and L, the members being constructed of independent strips of flexible sheet metal.

The member K is provided with an up-standing flange k having its upper portion 5 k^2 bent outwardly, and outstanding side flanges k^3 k^4 , this strip member being formed by doubling the strip upon itself intermediate its side marginal portions. The strip L has the double wall extending up-standing flange l the upper portion l^2 of 10 which is bent to extend at an upward inclination, and the strip has outstanding flanges l^3 l^4 . The strip members K—L are assembled in interfitting relation, as shown, 15 with the outstanding flange k' of the member K overlapping and fitting against the outstanding flange k^3 of the member K. The members K—L interfitting one with the other are secured together in adjusted position upon the upper face of the sill of the 20 window frame by a row of tacks or other suitable fastening members m passing through the overlapping outstanding flanges k^3 and l^3 of the respective members.

25 It will be observed that my improved weather strip provides a double barrier against the entrance of dust, moisture, air, etc., and the particular formation of the interfitting sealing portions of the sill strip 30 and the coöperating strip and parts on the sash constitute a very efficient weather proof fitting. The construction is of a strong, durable nature and can be economically manufactured from stock materials.

35 I desire it to be understood that minor changes and variations in the particular construction, illustrated in the drawings, as will appeal to those skilled in the art and within the scope of the appended claims may 40 be made without departing from the spirit of the invention.

What I claim is:

1. The combination with a casement window including a swinging sash, and a window frame having a sill, of a weather strip 45 comprising a metal strip element secured upon the lower face of the sash rail, said strip element having a substantially hook-shaped part forming a pocket at one side marginal portion thereof and a flat downwardly inclined sealing portion at its other side marginal portion; and a metal strip element secured upon the upper face of the 50 sill of the window frame, said last mentioned strip element having a pair of up-standing flanges separated from each other to form a channel therebetween, one of the flanges having its upper portion bent outwardly at an angle, the outwardly bent portion fitting within the pocket of the sash strip, and the other of said flanges being 55 flat and extending vertically, said last mentioned flange having a flat upper portion extending at an upward inclination corresponding to the angle of inclination of and

fitting flat against the outer face of the downwardly inclined sealing portion of the sash strip over a substantial area transversely of the strips when the sash is in closed position.

70

2. The combination with a casement window including a swinging sash, and a window frame having a sill, the lower rail of the window sash being provided with a rabbet at its lower outer marginal portion, of a weather strip comprising a metal strip element secured upon the lower face of the sash rail, said strip element having a substantially hook shaped part forming a pocket at one side marginal portion thereof and a flat downwardly inclined sealing portion at its other side marginal portion extending from the inner wall of the rabbet in the sash; and a metal strip element secured upon the upper face of the sill of the window frame, said last mentioned strip element having a pair of up-standing flanges separated from each other and providing a channel therebetween, one of said flanges having its upper portion bent outwardly at an angle, the outwardly bent portion fitting within the pocket of the sash strip, and the other of said flanges having a flat upper portion extending at an upward inclination over and flat against the outer face of the downwardly inclined sealing portion of the sash strip with its upper marginal portion extending beneath the upper wall of the rabbet in the sash and fitting against the said upper wall at the inner edge thereof when 95 the sash is in closed position, said straight upper inclined portion of one strip and the straight downwardly inclined portion of the other strip being of substantial width and fitting against each other over a substantial 100 area transversely of the strips.

95

3. The combination with a casement window including a swinging sash, and a window frame having a sill, of a weather strip 110 comprising a metal strip element secured upon the lower face of the sash rail, said strip element having a substantially hook-shaped part forming a pocket at one side marginal portion thereof and a flat downwardly inclined sealing portion at its other side marginal portion; and a metal strip element secured upon the upper face of the sill of the window frame, the last mentioned strip element being constructed from a single strip of flexible sheet metal doubled upon 115 itself intermediate its side edges at different points to provide a pair of up-standing double walled flanges spaced apart, with an intermediate horizontal connecting base portion, and horizontal base flanges at the sides 120 of the up-standing flanges, one of said up-standing flanges having its upper portion bent outwardly at substantially right angles, said outwardly bent portion being adapted 125 to fit within the pocket of the sash strip, and

130

the other of said upstanding flanges having an upper flat portion extending at an upward inclination corresponding to the angle of inclination of and adapted to fit flat against the outer face of the downwardly inclined sealing portion of the sash strip when the sash is in closed position.

In testimony whereof I hereunto affix my signature in the presence of two witnesses.

JOSEPH P. GLASER.
